CHARLES HORN, OF MILLBOURNE, PENNSYLVANIA, ASSIGNOR, BY MESNE ASSIGNMENTS, TO HARVEY HUBBELL, INC., OF BRIDGEPORT, CONNECTICUT, A CORPORATION OF CONNECTICUT.

COMBINED CABLE CLAMP AND BUSHING.

1,142,709.

Specification of Letters Patent. Patented June 8, 1915.

Application filed April 3, 1914, Serial No. 829,179. Renewed May 1, 1915. Serial No. 25,309.

To all whom it may concern:

Be it known that I, CHARLES HORN, a citizen of the United States, residing at Millbourne, in the county of Delaware and State 5 of Pennsylvania, have invented a Combined Cable Clamp and Bushing, of which the following is a specification.

This invention is designed to provide improved means for securing electric cables to 10 outlet boxes, an object being to obtain flexibility that will permit satisfactory clamping while providing a satisfactory bushing.

In the accompanying drawings, Figure 1 is a sectional elevation of my improved device combined with a box and armored cable, taken on the line 1—1 of Fig. 2; Fig. 2 is a sectional view taken on the line 2—2 of Fig. 1; Fig. 3 is a front elevation of an open box with the device therein; Fig. 4 is a perspective view of the detached device; and Fig. 5 is a perspective view of a modified 20 form of the construction.

The mechanism shown in Figs. 1 to 4 inclusive comprises a clamp and bushing having 25 the segmental bodies 1 provided with the inturned terminal rings 1^a connected by the web 2, having the inturned flange 2^a extending between the rings, and the web sections 3, 3^a and 3^b separated by the slits 3^c, the web 30 2 having a bearing 4 thereon. The device is engaged in the box 5 by a screw 6 which passes through the parts 3 and 4. Cables 7 provided with armor 7^a are passed through apertures 5^a in the box with which the bores 35 of the bodies 1 register, the ends of the armors 7^a abutting against the rings 1^a and the insulated covered conductors extending therethrough. The cable being in place, the screw 6 is run in, drawing in the web section 3 and pressing the extremities thereof 40 against the armor 7^a to clamp the cable securely. The box and cable are thus securely

coupled together by a device that avoids injury to the covering on the conductors, and provides the desired elasticity for clamping 45 without sacrificing strength.

As illustrated in Fig. 5, the curved and hollow bodies 1 with the inturned terminal rings 1^a are connected by the web 2 with the inturned flange 2^a extending between the 50 rings, and the web sections 3^d and 3^e separated by the slot 3^f, the bottom rib 3^g containing the notches 3^h in its section comprised in the part 3^d. The slot 3^f and the notches 3^h permit the section 3^d to be drawn 55 in readily and sections of the bodies at the ends thereof to be pressed in to secure more effectual clamping.

Having described my invention, I claim:

1. In a device of the character described, 60 a clamp and bushing comprising a pair of open bodies adapted for holding cables and webs connecting the terminals of said bodies, one of said webs being provided with a slot extending into said bodies.

2. In a device of the character described, 65 a clamp and bushing comprising open segmental body portions provided with closed end rings and webs connecting said body portions, one of said webs containing a slot. 70

3. In a device of the character described, 75 a clamp and bushing comprising a pair of segmental bodies, webs connecting the extremities of said bodies, said bodies and one of said webs being provided with a slot, and means coöoperating with said slot for facilitating the flexing of sections of said bodies.

In testimony whereof I have hereunto set my name this 26th day of March, 1914, in the presence of the subscribing witnesses.

CHARLES HORN.
